Herbert C. Ogden
HIS ATTORNEY.

UNITED STATES PATENT OFFICE.

SNOWDEN B. REDFIELD, OF EASTON, PENNSYLVANIA, ASSIGNOR TO INGERSOLL-RAND COMPANY, OF JERSEY CITY, NEW JERSEY, A CORPORATION OF NEW JERSEY.

LOCK FOR SELF-PACKING PISTONS.

Application filed July 15, 1926. Serial No. 122,715.

This invention relates to pistons, but more particularly to a lock for pistons of the self-packing type.

The objects of the invention are to prevent leakage of pressure fluid between the piston and its cylinder, to prevent separation of the parts comprising the piston and to insure free relative movement of such parts.

Other objects will be in part obvious and in part pointed out hereinafter.

The invention consists of the combination of elements and arrangement of parts having the general mode of operation substantially as described hereinafter and more particularly pointed out in the appended claims and illustrated in the accompanying drawing.

The figure in the drawing is a sectional elevation of a compressor unloader equipped with a piston constructed in accordance with the practice of the invention.

Referring to the drawing in which is illustrated one form which the invention may assume in practice, a piston *d* is provided with an external flange *e* of substantially the same diameter as the chamber *f* of the cylinder *c* and a body portion *g* of the piston *d* is adapted to cooperate slidably with a bore *h* of a reciprocable piston head *j* slidable in the chamber *f*. A cover plate *k* forms a closure for the end of the cylinder *f* and this cover may be secured in position by tap bolts *o* as indicated.

Pressure fluid for actuating the piston head *j*, the piston *d*, and consequently valves *U* and *H*, is conveyed thru a pipe *p* to the chamber *f*.

Means is provided for preventing separation of the piston head *j* and the piston *d*. To this end an external annular groove *q* is formed near the end of the body portion *g* of the piston *d* to receive an expandable spring ring *r* which cooperates slidably with an internal annular groove *s* formed in the rearward end of the piston head *j*. The groove *s* is preferably of considerable width so as to permit a rather wide range of relative longitudinal movement between the piston *d* and the piston head *j* for the purpose of compressing the packing *u* interposed between the flange *e* and an end *V* of the piston head *j* for the purpose of rendering the entire piston assembly leak-proof when

held stationary in the position shown and yet easily slidable to open the valve *H* upon removal of pressure fluid from the chamber *f*.

By means of the present invention, the parts which comprise the means for compressing the packing, that is, the piston *d* and the piston head *j*, may at all times be held effectively against separation with respect to each other. There are no loose parts which may be vibrated out of assembled position and lost as so frequently occurs where the mechanism of which they form a part is subjected to extremely hard usage. Furthermore, it is impossible, by means of this lock, to apply an excess quantity of packing *u*, through mistake, which would thereby so lengthen the piston assembly that the valve *H* might not be opened.

In assembling the piston *d* in the piston head *j*, the spring ring *r* may be placed in the annular groove *q* and the piston may then be inserted into the piston head *j* and pushed thereinto until the spring ring *r* passes the shoulder *t* in the piston head. The spring ring will then expand and the parts will be held thereby against separation. After the piston and the piston head have been thus assembled, the packing *u* may be interposed between the flange *e* of the piston and the end *V* of the piston head and the entire assembly will be in readiness to be placed in the cylinder chamber *f*. Subsequent replacements of the packing *u* may be readily made since it is merely necessary to remove the cover plate *k* from the cylinder *c* and the piston assembly may then be removed from the cylinder *c* and new packing supplied thereto in the manner described without necessitating the dismantling of the piston assembly.

A suitable application for the self packing piston above described is illustrated in the drawing wherein is provided a valve *T* adapted to be held seated by the pressure transmitted thru the piston *d*. The valve *T* is arranged to control the flow of fluid from a passage *B* to a passage *E*, both passages being formed in a body *A*.

I claim:

1. In a self-packing piston, the combination of a cylinder, a pressure fluid actuated piston head in the cylinder, a piston slidably in the piston head, an external flange on the

piston, packing between the flange and the end of the piston head to prevent leakage of pressure fluid from the cylinder, and a spring ring carried by the piston to cooperate with the piston head for limiting relative longitudinal movement between the piston and the piston head.

2. In a self-packing piston, the combination of a cylinder, a pressure fluid actuated piston head in the cylinder having an internal annular groove, a shoulder at one end of the groove, a piston slidable in the piston head, said piston having an external

annular groove, an external flange on the piston, a packing encircling the piston ¹⁵ adapted to be compressed by the flange and the end of the piston head for sealing the cylinder, and a spring ring in the external annular groove slidable in the internal annular groove to cooperate with the shoulder ²⁰ for preventing displacement of the piston from the piston head.

In testimony whereof I have signed this specification.

SNOWDEN B. REDFIELD.
